UNITED STATES PATENT OFFICE

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS

DOOR CONSTRUCTION

Application filed August 16, 1928. Serial No. 299,994.

My invention relates to building structures presenting relatively wide door-openings such as, and more particularly, aeroplane hangars, the door-openings in which are very wide and high, and wherein it is desired that the doors be shifted into and out of closing position.

The common practice in structures of this kind is to provide the door-opening within the confines of relatively wide door-jams projecting inwardly from the front ends of the side walls of the building and to provide sectional doors which hang from tracks at the top of the door-openings and are shiftable from a position in which they close the door-openings into a position in which they extend along the inside of the side-walls of the building, and vice versa.

The provision of the door-jams presents a number of disadvantages, some of which are the added expense of constructing the building because of such jams and the reduction in the capacity of the building due to the restricted door-opening resulting therefrom.

My primary object is to provide a structure wherein the doors are movable from closed position into a position alongside of the side-walls of the building, and vice versa, without requiring the use of door-jams with the manifest advantages.

Referring to the accompanying drawings:—

Figure 1 is a plan sectional view, somewhat diagrammatic, of the front end of an aeroplane-hangar constructed in accordance with my invention, the section being taken immediately above the door, one-half only of which is shown, and the roof-outline being shown by dotted lines.

Figure 2 is an enlarged view taken at the line 2—2 on Fig. 1 and viewed in the direction of the arrows, this view being an inside face view of a portion of the front of the building at the door-opening and one of the similar sets of door-sections employed.

Figure 3 is a plan sectional view of one of the front corners of the hangar, showing a portion of the door in closed position and the track along which the door operates, the

section being taken at the line 3 on Fig. 4 and viewed in the direction of the arrow; and

Figure 4, an enlarged section taken at the line 4 on Fig. 3 and viewed in the direction of the arrow.

Referring to the particular illustrated embodiment of my invention, the front portions of the side-walls of an aeroplane-hangar are represented at 5, and the upper front wall of the hangar, which defines the upper boundary of the door-opening 6, is represented at 7, the extreme front edge-portions of the side-walls 5 being preferably provided at their inner surfaces with relatively thin batten-strips 8.

The door for the structure shown is formed of a plurality of edgewise opposing sections 9, there being twelve of these sections in this particular structure. The sections 9 are grouped into sets of three each, the sections 70 of each group being hinged together as represented at 10 to permit the sections to swing inwardly relative to each other.

The door-sections 9 are supported on a track-structure to permit them to be moved 75 from the position shown of the six sections at the left-hand side of Fig. 1 and as shown in Fig. 3 wherein the door-opening is closed, into a position in which six of the sections extend alongside of the front portions of one of the side-walls 5, and the other alongside the other side wall as shown of the six sections at the right-hand side of Fig. 1 in which position the door-opening is uncovered.

The track-structure shown comprises a track 11 which extends along the inner side of the front wall 7 in parallelism therewith throughout the greater portion of the length of the latter but short of the ends thereof, the ends of this track curving rearwardly, as represented at 12 of the one end shown in Fig. 3, to points spaced from the side-walls, as represented at 13 of one end of the track in Fig. 3.

The track structure also comprises tracks located at the inner sides of the side-walls 5 and closely adjacent thereto and parallel therewith which extend from the front wall 7 distances rearwardly thereof each greater

than the combined width of six of the door-sections 9, with gaps in each of these tracks adjacent the inner extremities of the curved portions 12 of track 11.

The one of the tracks above referred to and which extends along the side-wall 5 shown in Fig. 3 is represented at 14 and the gap referred to at 15, this structure being duplicated at the opposite side-wall.

10 The track-structure further comprises a switch track section at the gap in each of the two side-tracks, as shown at 16 of the track illustrated in Fig. 3, these switch track-sections being pivoted to the side-tracks 14 at the rear ends of the gaps therein, as illustrated at 17 of the track in Fig. 3, and adapted to be swung into alinement, at their free ends, with either the rear ends of the tracks 14 at the front ends of the gaps 16 as shown 15 by full lines of the track in Fig. 3, or with the rear ends of the curved portions 12 of track 11, as shown by dotted lines in this figure.

15 The tracks and switches are each of the type comprising a pair of spaced apart angle-irons 18 and 19 connected together in any suitable way, with spacers 20 interposed between their vertical flanges, the horizontal flanges of the angle-irons forming ways at 20 which twin-wheeled hangers 21 swiveled at 22 to the door sections 9 and by which the door-sections 9 hang, are supported for movement along the tracks, the angle-irons of the stationary tracks being secured in position 25 by lag-bolts 23 mounted to depend from timbers 24 secured to the building structure in a plane above the door-opening.

30 The switch track sections 16 are supported in any desirable way from the structure above them and in practice means (not shown) positioned to be readily actuated by the operator, would preferably be provided, for shifting the switches alternately to the positions above referred to.

35 From the foregoing description it will be noted that, assuming the door is in closed position, in which the end ones of the hangers 21 extend at the extreme forward ends of the tracks 14 and the intermediate hangers engage the straight portion of the track 11, and it is desired that the door be opened, the operator pushes the extreme end ones of the sections 9 toward the back of the building, the end hangers 21, in this operation traveling rearwardly along the track 14 and drawing the two sections 9 connected with each thereof along the track 11 toward the respective side-walls 5, the hangers on these other door sections traveling along the curved portions 12 of track 11. After the end hangers have passed the switches 16 the operator throws these switches into alinement with the ends of the curved portions 12 of track 11 and by continuing the movement of the door-sections 9 toward the rear of the building causes

40 all of these hangers of these two end groups of door-sections to extend along the portions of the tracks 14 to the rear of the gaps 15. The remaining two groups of door-sections may then be moved along the track 11 in opposite directions onto the tracks 14, respectively, at opposite sides of the building. If desired the switches may then be returned to a position in which they span the gaps 15 and the two groups of door-sections at each 45 side of the building moved forwardly along the tracks 14 to points closely adjacent the front of the building.

45 To close the door, the door-sections, if positioned as just stated, are pushed backwardly to pass wholly rearwardly beyond the switches 16, the switches then swung into alinement with the curved portions 12 of the tracks 11 and the door-sections moved, toward the center of the door-opening, along 50 the tracks 11. When all but the last door-hangers of the two end groups of door sections have passed the switches 16 the switches are swung back to fill the gaps 15 and these last hangers are then pushed forwardly along 55 the front ends of tracks 14 to the position shown of the one hanger at the extreme left-hand side of Fig. 3.

55 From the foregoing it will be noted that by constructing a building in accordance with my invention the requirement for relatively wide door-jams presenting the objections hereinbefore noted is avoided, while permitting of the withdrawal of the door sections to a position in the building wherein they 60 are out of the way, thereby permitting practically the full capacity of the building to be utilized.

65 While I have illustrated and described a particular embodiment of my invention, I do not wish to be understood as intending to limit it thereto as the same may be variously modified and altered without departing from the spirit of my invention.

70 What I claim as new, and desire to secure by Letters Patent, is:

75 1. In combination with a building structure containing a door-opening, a door therefor comprising a horizontal series of door-sections end ones of which are hingedly connected together, and tracks for guiding said sections into closed position and into a position in which they extend substantially parallel with, and alongside of, the side-wall portion of the building, one of said tracks 80 extending substantially parallel with, and alongside of, said side wall to a point closely adjacent said door-opening, with a gap in said track, and another of said tracks extending along said door-opening with the end thereof adjacent said first-referred-to track extending in a rearward direction, and a switch movable into a position spanning said gap and into a position in which it connects said second-referred-to track with said 85

- side-track, said end door-section engaging said first-referred-to track in the closed position of the door whereby in the guiding of the door sections to open position the switch must be thrown while said end door-section engages both of said tracks.
2. In combination with a building structure containing a door-opening, a door therefor comprising a horizontal series of door sections end ones of which are hingedly connected together, substantially alined front and rear track sections extending along a side wall portion of the building and spaced apart at their adjacent ends, said front track section extending closely adjacent said door opening, a third track section extending along said door opening and extending rearwardly toward said first-named track sections and spaced therefrom at its adjacent end, a switch track adapted to span the space between said first-named track sections or the space between said rear track section and said third track section, and means on said door sections engaging said tracks.
3. In combination with a building structure containing a door opening, a door therefor comprising a plurality of horizontal series of door sections end ones of each of said series being hingedly connected together, substantially alined front and rear track sections extending along each of opposite side wall portions of the building, said front and rear track sections being spaced apart at their adjacent ends and said front sections extending closely adjacent said door opening, a third track section extending along said door opening and at its ends rearwardly toward the front and rear track sections at the respective sides of the building, said third track section being spaced from said front and rear track sections at its rearwardly extending ends, switch tracks adapted to span the spaces between the front and rear track sections or the spaces between said rear track sections and said third track section, and means on said door sections engaging said tracks.
4. In combination with a building structure having a door opening, a single line track adjacent the door opening extending partly lengthwise with respect thereto and then laterally and rearwardly, a single line track extending rearwardly from the opening, the rear end of the first mentioned track terminating intermediate the ends of the second mentioned track, a door, first and second supporting means for the door, said first and second supporting means being mounted on the first and second tracks respectively, in the closed position of the door, and means at the junction of the tracks enabling the first supporting means to be moved from the first mentioned track to the second mentioned track through movement of the door and the door to then be moved with the
- first and second supporting means traveling on the second mentioned track to dispose a portion of the door forwardly of said junction.
5. In combination with a building structure having a door opening, a single line track adjacent the door opening extending partly lengthwise with respect thereto and then laterally and rearwardly, a single line track extending rearwardly from the opening, the rear end of the first mentioned track terminating intermediate the ends of the second mentioned track, a door, first and second supporting means for the door, said first and second supporting means being mounted on the first and second tracks respectively, in the closed position of the door, and a switch member movable to form a section of either track located at the junction of the tracks enabling the first supporting means to be moved from the first mentioned track to the second mentioned track through movement of the door and the door to then be moved with the first and second supporting means traveling on the second mentioned track to dispose a portion of the door forwardly of said junction.
